[57] **CLAIM**

The ornamental design for an upper rib for a planer, as shown and described.

DESCRIPTION

FIG. 1 is a left side perspective view from the front of upper rib for a planer showing my new design;

FIG. 2 is a top plan view of my design; and,

FIG. 3 is a front elevational view of my design.

In the attached drawings, any broken line illustration is not part of the design sought to be patented.
